ATTORNEY.

UNITED STATES PATENT OFFICE.

STANISLAW MACKIEVICZ, OF DENVER, COLORADO, ASSIGNOR OF ONE-HALF TO JOHN A. NEWARK, OF DENVER, COLORADO.

LIFE-BOAT.

1,188,465.

Specification of Letters Patent. Patented June 27, 1916.

Application filed March 1, 1916. Serial No. 81,391.

To all whom it may concern:

Be it known that I, STANISLAW MACKIEVICZ, a subject of Nicholas II, Czar of Russia, residing at Denver, in the county of 5 Denver and State of Colorado, have invented certain new and useful Improvements in Life-Boats, of which the following is a specification.

This invention relates to life boats, and its 10 primary object resides in the provision of a boat the buoyancy of which is increased by means of fluid filled compartments and tubes arranged and proportioned to keep the vessel afloat even after it is partially filled with 15 water by leakage or heavy seas.

Another object of my invention resides in providing means for propelling and steering the boat, which are constructed and arranged so that one person seated within the boat 20 can operate both devices.

A still further object of my invention is to provide means whereby a canopy or cover can be tightly stretched over the entire boat to shield the occupants thereof from wind 25 and water.

With the above and other objects in view, all of which will fully appear in the course 30 of the following description, my improved boat consists of the construction and arrangement of parts shown in the accompanying drawings in the various views of which like parts are similarly designated, and in which,

Figure 1 is a plan view of my improved 35 life boat, Fig. 2, a longitudinal section along the line 2—2, Fig. 1, Fig. 3, a transverse section taken along the line 3—3, Fig. 2, drawn to an enlarged scale, and Fig. 4, a detail view of the mechanism for operating the 40 propelling and steering devices of the boat.

Referring more specifically to the drawings, the numeral 2 designates the hull of a boat provided interiorly with side seats 3 and transverse thwarts 4. Applied exteriorly of the hull is a continuous band 5 of tubular flexible material placed between two series of outwardly projecting arms 6 which at their outer ends carry hand-rails 7 which completely surround the hull of the boat. 45 The tubular band has a valve-closed nipple 22 by which it may be filled with an elastic fluid such as air, and the rails extend beyond the outer surface of the band in order to protect it against damage by objects with 50 which the boat comes in contact.

A curved or arched support 8 extends from stem to stern in the vertical plane of the longitudinal axis of the boat for the attachment of a canvas canopy 9 shown in Fig. 3. The support is provided with hooks 60 10 which are arranged in two series at opposite sides of its center. The hooks comprised in the two series are bent in opposite directions so that a canopy having a corresponding number of rings or eyelets in a line intermediate of its longitudinal edges can be stretched lengthwise of the support. The gun-wale 12 of the boat has exteriorly a series of outwardly projecting hooks 13 to secure the edges of the canopy, which to this 65 end are likewise provided with rings or eyelets. It will be seen that a canopy or cover thus stretched and supported, covers the entire extent of the boat and effectively shields the occupants thereof against wind and water, windows 14 being provided to admit 70 light to the interior of the boat.

A false bottom 15 provides an air-tight compartment 16 extending lengthwise of the boat, and partitions 17 provide similar compartments 18 and 19 at the bow and stern of 75 the same.

Extending beneath the side seats and thwarts of the boat are tubes 20 of elastic material which are connected into a series of 80 cross tubes which communicate for the passage of fluid from one to the other. The series of cross tubes within the boat and the tubular band disposed exteriorly of the same, connect with the compartments at the bow 85 and stern of the boat as shown at 21 in Fig. 2, so that air or other fluid introduced into the band 5 through the nipple 22 will pass into the compartments and the hollow web and by filling the same increase the buoyancy of the vessel. 90

The boat is steered by means of a rudder 23 and moves through the water by a screw propeller 24 both of which are mounted at the stern of the hull. The propeller is rotated by means of a hand-operated mechanism the construction of which will now be described. 95

A pair of standards 25 erected upon the bottom of the boat, carry at their upper ends 100 a shaft 26 which at its extremities is provided with oppositely extending hand-cranks 27. A sprocket wheel 28 mounted upon the shaft between the standards, is by means of a chain 29 connected with a similar 110

wheel 30 of smaller diameter which is carried on a shaft 31 mounted in bearings adjacent the lower ends of the standards, and the last-mentioned shaft is operatively connected with the shaft 32 of the propeller by a pair of coöperative beveled gear-wheels 33 and 34.

The rudder mounted for rotation about a vertical axis abaft the stern of the boat, is 10 steered by means of a yoke 35 which is fixed on its shaft within the boat.

A pair of treadles 36 pivoted exteriorly of the standards 25, preferably upon the ends of the shaft 31, are connected with the corresponding ends of the rudder yoke by means of rods 37 and they are yieldingly maintained in their normal position by means of springs 38 which connect them with a relatively stationary part.

20 It will be seen from the above that one person seated at the stern of the boat can propel the boat by rotation of the crank shaft and at the same time steer the boat by pressing the treadles with the foot.

25 The advantages obtained by a boat constructed as herein described, will be apparent.

The fluid-filled tubes and compartments give stability to the hull and greatly increase the buoyancy of the same. The surrounding hand rails while protecting the exterior, tubular band, provide ready means for saving people, since they can be grasped by a great number of people in the water.

The simple means for steering and propelling the boat, require the attention of but one person, thereby affording to the other occupants of the boat, full opportunity of assisting persons in the water in entering the boat.

I desire it understood that while I have shown and described my invention in the best form at present known to me, variations in the construction and arrangement of its parts may be resorted to within the spirit 40 of my invention as set forth in the appended claims:

1. A life-boat comprising a hull having air-tight compartments, hollow tubes within the hull connected with said compartments, 50 a surrounding band exteriorly of the hull in communication with said compartments, and means for introducing a fluid into said connected parts.

2. A life-boat including a hull having air-tight compartments, tubes within the hull, connected into series of cross-tubes and a surrounding tube exterior of the hull, said tubes both within and without the hull communicating with said air-tight compartments and means for introducing a fluid into said connected parts.

In testimony whereof I have affixed my signature in presence of two witnesses.

STANISLAW MACKIEVICZ.
